RECEPTACLE CLOSURE

Charles J. Jesnig, Philadelphia, Pa., assignor to
Positive Seal Closure Company, Philadelphia,
Pa., a corporation of Delaware

Application March 11, 1936, Serial No. 68,158

4 Claims. (Cl. 215—26)

This invention relates to receptacle closures, with particular reference to closures of the so called non-refillable type.

In earlier applications, numbered Ser. No. 5 756,021 and Ser. No. 33,450, there was disclosed the detailed structure and function of a valve and valve assembly for receptacles, and particularly for bottles, that marked a great advance over the known art, in the provision of a simple, economical, rugged assembly that could be easily 10 manufactured and installed, and which was non-refillable as far as commercial possibilities were concerned, even including efforts to refill under a vacuum. However, under certain favorable 15 conditions, and utilizing all necessary time and elaborate apparatus for the purpose, it was in some instances a laboratory possibility to introduce liquid to the valve of the applications noted, under a slight gravity head, or the like, while the receptacle was inverted and inclined, by 20 which a slow seepage into the receptacle was possible. This was necessarily slow, and attempts to increase the rate of fill simply caused the valve to shut to prevent further ingress of fluid. The use of the variable gravity head, or 25 the like, on the inverted opened valve, while being impractical from any commercial viewpoint, so far as understood, was a form of procedure by which some sort of refilling might 30 occasionally occur and was therefore a potential criticism of the supposedly non-refillable receptacle of the prior applications. It is to be observed also that even a perfect non-refillable type of bottle cannot be sold if its price is too 35 high, and that as between devices of even only superficial similarity of effectiveness, the cheaper device is the one ordered, so that reductions in costs of production are of importance.

It is among the objects of this invention: to 40 improve generally the art of non-refillable receptacles; to provide a receptacle closure with a float controlled valve arranged to permit outward pouring while the bottle, of course, is inverted and inclined, but arranged to close by flotation when the fluid flow is inward of the bottle 45 while in the same inverted and inclined position; to provide improvements in the inventions shown in said earlier filed applications; to provide improved means for preventing insertion of wires 50 into such non-refillable bottles, and other receptacles; to provide a valve device for bottle closures with means such as to generate a valve closing pressure in response to inward fluid motion; to provide a substantially non-refillable 55 bottle with a minimum of parts and of small

cost; to provide the parts of a non-refillable closure such that each can be molded from plastic material; and many other objects and advantages as will become more apparent as the description proceeds.

The invention will be shown and described in connection with a bottle as the particular type of container or receptacle which is preferred, and for illustration purposes only, as it will be evident that the invention can be applied to any 10 other sort of container or receptacle, such as jars, drums, tanks, metal bottles and the like, and such scope of application and use is contemplated herein.

In the accompanying drawing: 15 Fig. 1 represents a fragmentary vertical section through the upper end of a bottle neck with the improved valve assembly of the invention shown in closed position, and with the opened position shown in dotted lines.

Fig. 2 represents a fragmentary vertical section through a valve and valve housing of modified form, and 20

Fig. 3 represents a fragmentary plan of the valve element and housing.

Referring to the purely illustrative disclosure of Fig. 1, it will be observed that a valve seat housing 10 is provided, having a lower valve seat portion 11, which is preferably planar and is provided with an axial hole 12. The housing comprises the outwardly extending rim portion 13, and the connecting, preferably substantially cylindrical, housing and guiding portion 14. In the usual case the rim portion of the housing will be supported on a gasket 15, on the mouth or rim 16 of a bottle, of which the fragmentary neck portion 17 only is disclosed. It is preferred that the valve seat 11 be of a hardened or glazed and non-porous finish where the valve, to be described, engages the seat, and in the interests of cheapness and simplicity, as well as of a hard finished non-porous valve seat, will comprise a molded or die cast material of plastic nature, as of some of the chemical plastics that are now available as later recited. This material is preferred for use throughout, with a possible exception that will be explained. The valve housing described hangs within the neck of the bottle, either from the rim as shown, or from an interval shoulder as disclosed in the above mentioned applications.

The valve element 18 is preferably in the form of a single or double ended cup, although for purposes of explanation the double cup is preferred and will be described. As shown in Fig. 1, 55

the valve is generally in the shape, in section, of a letter H with the cross bar usually below the center. Specifically the valve comprises a lower valve cylinder 20, the lower peripheral edge 21 of which has a sealing engagement with the surface of the valve seat 11. The lower cylinder is terminated by the transverse web 22, and comprises a relatively small cup against which outwardly pouring liquid in the bottle can strike to force 10 the valve off of its seat.

The upper portion of the valve comprises the substantial cylinder 23 arising from the web 22. This provides a cup having several functions. One important feature being to form a buoyant 15 chamber causing the valve to float to seating when it is attempted to fill the inverted bottle by a small gravity head of liquid, another being to force the valve to seating when an attempt is made to refill the bottle in its upright position 20 by pouring liquid downwardly from above, another being to form a small reservoir to hold liquid left in the mouth at the termination of pouring to prevent its seepage down the outside of the bottle neck by leakage out from under the 25 seal to be described. Another function is to form an upper part of the valve in such manner that it cannot be grasped or engaged by an inserted wire. A further function is found in the provision of an elongated member such as to support 30 fins to be described. The transverse web and open upper cylinder afford further means to receive a valve stop extending vertically into the cylinder to limit valve movement.

The valve 18 is dropped and seated gravitationally in the valve seat housing, in substantially concentric relation to the cylindrical wall 14 thereof. In order to maintain suitably guided 35 relation of the parts, it is preferred to provide a plurality of fins 24 between the valve and valve housing, which are preferably mounted radially on the cylinder 23 of the valve, and have easy 40 sliding relation with the cylinder wall. It will be clear that with the parts as shown in Fig. 1, inverting the bottle will cause the contained 45 liquid to travel up the neck to impingement against the lower cup, thus driving the valve from the seat and permitting the contents to be poured from the bottle. An interesting and important function of the lower valve cup lies in 50 the fact that it provides a piston structure with relation to which differential air pressures, as might be incident to attempts to fill the bottle under a vacuum, causes the valve to snap shut, and to stay shut under further attempts to fill 55 the bottle. The vacuum closing of the valve is effective as well during efforts to unseat the valve by impacts on the bottle aimed to cause surges of liquid in the bottle to impingement against the valve to unseat same. It is found that despite 60 the absence of a flexible washer as in certain of my earlier cases, or as shown in Fig. 2, the valve, even if unseated momentarily by the surges noted, will immediately snap shut again before any more liquid can be forced into the 65 bottle, due, in part at least, to the lower cup formation.

The closure comprises further a combined wire guard and valve stop of simplicity and which is also preferably formed of an integral molding of 70 a plastic material. The material of all parts of this device may be formed of a phenolic condensation product, or of casein, or urea, or the like, or of vulcanized materials, such as rubber and the like. The wire guard comprises a transverse 75 wall 25 from the center of which depends the

valve stop 26, arranged to extend into the upper valve cup, in such spaced relation as to enable the valve to unseat to proper pouring clearance before engaging the end of the stop 26. The outer periphery of the plate or wall 25 merges into the interrupted substantially perpendicularly extending cylinder 27 having the peripherally elongated pouring ports 28, and which cylinder merges into the short rim 30. In effect the interrupted cylinder is a continuation of the valve 10 housing cylinder 14.

The pouring spout and wire guard comprises the outwardly tapered member 31 having the restricted axial spout 32 which is preferably externally threaded as at 33, to receive a cap 34. 15 The enlarged end 35, of the spout structure includes a bead or flange 36 provided with an annular recess 37 within which the rim 30 of the wire guard is disposed to anchor the latter firmly in position. In the preferred embodiment of the 20 invention the entire assembly is held rigidly and firmly on the bottle by the metallic or other shell 39, having the upper constriction 38 to engage over the bead 36 of the spout, and having the skirt 40 arranged to be spun into the peripheral 25 groove 41 of the bottle neck after the parts are in place.

In the modification shown in Fig. 2, the valve seat housing comprises the substantially cylindrical portion 42 terminating at the bottom in the inwardly extending seat portion provided with the annular bead or valve seat peak 43, surrounding the aperture 44. The valve comprises the cylinder 45, having the closed lower end 46, open at the upper end toward the pouring spout, 30 and provided with the flexible washer 47 having the margin 48 arranged to overlie the seat peak 43. The washer disclosed functions as shown in the earlier mentioned applications and need not be further mentioned at this point other than to 40 mention that it is arranged to flex axially in both directions. The valve 45 has guide fins 50. The advantages of this structure will be obvious.

The utility of the wire guard will be better understood by reference to the dotted lines of 45 Fig. 1, by which an exaggerated spout structure is indicated to insure utmost efficiency as regards tamper proofness. In the full line disclosure the same factors maintain consonant with enhancement of the ease of pouring. The spout closely 50 surrounds the disc, both laterally and axially, until it diverges about shoulder 50, and thereby a plurality of relatively staggered shoulders is secured, so that an inserted wire must first bend about shoulder 50, then about the upper edge of 55 disc 25, then about the lower edge of disc 25 into aperture 27, and thereby such bending is secured as either to break the wire, or to so divert it that it cannot engage any part of the valve. A form of description would be that cylinder 27 if prolonged intersects the spout remote from the opening. The provision of bottle shoulder 51 insures, when tightly engaged by housing 14, 60 that air is so entrapped in the space externally of the housing, that no liquid enters, and so that 65 all of the contents are directed toward aperture 12.

I claim:

1. In a closure for a container having a neck, a primary flanged section having a reduced neck portion and a pouring opening therein, a substantially cylindrical valve-containing secondary section flanged at both ends, an intermediate section forming a guard comprising an imperforate disc, a perforated disc of larger diameter than 75

said imperforate disc and spaced connecting means extending substantially perpendicularly of the perforated disc and forming horizontal radial openings between the discs, means formed on contiguous portions of the flange of the primary section and a flange of the secondary section to receive said larger diametered disc, said primary and secondary sections being disposed in relative juxtaposition, a flat washer-like gasket about said 5 valve-containing section, and container-engaging means to abut the flange of the upper section and thereby permanently to secure the perforated disc in said means and a flange on each of said sections in superposed relation on said gasket 10 and against the outer end of the container neck.

2. In a closure for a container having a neck, a primary flanged section having a reduced neck portion and a pouring opening therein, a secondary hollow substantially cylindrical valve-containing section having at one end a flange forming a valve seat and port and at the other end a flange in axial alignment with the flange on the primary section, an intermediate section comprising two spaced discs of different diameters the larger disc being centrally apertured and positively engaged between the said axially aligned flanges of the primary and secondary sections, a hollow valve in said lower section having an annular seat engaging portion and having 20 a horizontal web forming a float chamber in the valve, valve movement limiting means on said intermediate section, and container engaging means abutting the flange on the primary section and thereby securing the flange on the secondary section against the end face of the 25 container neck.

3. In a closure for a container having a neck, a primary flanged section having a reduced neck portion and a pouring opening therein, a substantially cylindrical valve-containing secondary section having an internal flange and an external flange at its respective ends, the flange of the primary section and the external flange of the secondary section being juxtaposed, and the internal diameter of the secondary cylindrical section being smaller than the internal diameter of the primary section adjacent its flange, a wire 30 guard comprising an imperforate transverse annular disc disposed within the primary section 35 in spaced relation thereto of a diameter not less than the inner diameter of said substantially cylindrical section, and an integral perforated

disc of larger external diameter than the imperforate disc and spaced axially from said imperforate disc, connecting means between the discs to form laterally extending apertures beneath the said imperforate disc, means engaging the larger disc between the juxtaposed flanges to anchor the wire guard, a valve movable in the container, means for guiding the valve in the container in substantially centered relation and stop means mounted on the imperforate disc extending 10 into the valve to limit its movement relative to the internal flange of the secondary section, and means engaging the primary section and a bottle neck to pull the juxtaposed flanges together and into seated engagement relative to the end of a 15 bottle neck.

4. In a closure for a container having a neck, a primary flanged section having a reduced neck portion and a pouring opening therein and a flanged end, a substantially cylindrical valve-containing secondary section having an internal valve seat flange and an external supporting flange at its respective ends, the said flanged end and the said supporting flange being substantially 20 juxtaposed, and the internal diameter of the secondary cylindrical section being smaller than the internal diameter of the primary section adjacent its flanged end, a wire guard comprising an imperforate transverse annular disc disposed within the primary section in spaced relation thereto of 25 a diameter substantially similar to the external diameter of said substantially cylindrical section, and the wire guard having a perforated disc of larger external diameter than, and spaced axially from, said imperforate disc, connecting means 30 between the discs to form laterally extending apertures beneath the said imperforate disc, the larger disc disposed in part between the substantially juxtaposed flange and the flanged end to anchor the wire guard, a valve movable in the 35 secondary section, means for guiding the valve in the secondary section in substantially centered relation, stop means mounted on the imperforate disc extending toward the valve to limit its movement, and means engaging the primary section 40 and a bottle neck to pull the substantially juxtaposed flanges toward each other and to anchor all of the parts except the valve in relatively fixed mutual relation and into seated engagement 45 relative to the end of the bottle neck. 50

CHARLES J. JESNIG.
